UNITED STATES PATENT OFFICE.

WILLIAM J. MCCOY AND BART DEAN, OF JEFFERSONVILLE, INDIANA.

BOLSTER FOR CAR-TRUCKS.

SPECIFICATION forming part of Letters Patent No. 242,670, dated June 7, 1881.

Application filed April 27, 1881. (No model.)

To all whom it may concern:

Be it known that we, WILLIAM J. MCCOY and BART DEAN, citizens of the United States, residing at Jeffersonville, in the county of 5 Clarke and State of Indiana, have invented new and useful Improvements in Top Bolsters for Railway-Car Trucks, of which the following is a specification.

This invention relates to top bolsters for car-trucks, the object being to provide a simple means whereby the bolster may be formed of two separate beams united by blocks and plates in such a manner as to leave between them an intervening space or spaces for the passage of necessary bolts, and thus obviate the danger 10 of weakening the bolster arising from boring it at the center for the passage of the king-bolt; and the invention consists in the construction and arrangement of parts, as herein- 15 after more fully described and claimed.

In the accompanying drawings, which fully illustrate the invention, Figure 1 is a side view of a car-truck embodying our improvements. Fig. 2 is a side view of our improved bolster, 20 partly in section. Fig. 3 is a top view; and Fig. 4 is a transverse section.

Like letters indicate like parts in the several views.

A are the wheels, B the journal-boxes, and 25 C C' C² are iron frames or bars attached to and connecting the journal-boxes with the bolsters.

The lower bolster, D, rests upon the lower bars, C, and supports rubber blocks or other suitable springs, E E, of any desired construction, upon which, in turn, rests the top bolster, F, that passes under the upper arch-bar, C. On the sides of the bolster F, at each end, are guide-blocks F', which are grooved for engagement with the vertical bars C' C', upon which 30 they slide. By this means the bolsters have a flexible connection with the journal-boxes that prevents undue strain from sudden jars in passing over unequal tracks.

In order to overcome some of the more common difficulties experienced in obtaining well-seasoned timber of suitable dimensions for the top bolsters of car-trucks, and also to avoid the necessity of boring such bolsters at the center for the passage of the king-bolt, it has 45 been found of advantage to construct the bolster of two separate beams, which may, if de-

sired, be of less than half the size that would be otherwise required, and, if properly braced and connected, will be of equal, if not increased, strength. These beams *a a* are placed parallel 55 to each other and separated by intervening blocks *b*, that are secured between them at the ends of the bolster. The blocks *b* extend far enough to support the side bearings, *b'*, and are of such width or thickness that a space of 60 about two inches, preferably, is left between the side beams.

At the center of the top bolster are the top and bottom plates, G H, which are formed with central lugs or strut-flanges, *c*, that pass 65 between the beams *a a* for the purpose of holding them apart. These plates G H are also provided with pins or nipples *d*, which enter the side beams, *a a*, and prevent them from spreading or springing. The top and bottom 70 plates are securely attached to the bolster-beams and to each other by tie-bolts *e*, that enter openings *e'* and pass through the lugs *c* in the space between the beams. At their ends the side beams are securely connected by 75 the guide-bolts *f f*, that secure the guide-plates F' in place, and also pass through the blocks *b*. These are the only bolts that pass through the timber of which the bolster is composed, and therefore the liability of undue strain and 80 weakness at these points, where openings for bolts are ordinarily required, is largely diminished.

The bolster is firmly braced by the longitudinal truss-rods *g g*, which are connected at 85 their ends by cross bars or ties *g' g'*, that are secured by suitable nuts and rest against inclined shoulders formed in the upper part of the beams. These truss-rods engage with the usual grooved projections, *h h*, on the lower 90 center plate, H, and thus centrally sustain the two spaced beams composing the bolster.

In the center of each of the metal plates G H is an opening, *i*, for the reception of the king-bolt, which passes through the space between the beams *a a*. 95

It is evident that as by this construction the usual necessity of boring the bolster at this point is obviated the consequent danger of strain and liability of fracture therefrom is 100 also avoided.

By this construction it is also possible to

employ timbers of less than the dimensions ordinarily required, which involves an additional advantage, as such timbers may be obtained more conveniently and cheaply, and 5 usually are better seasoned.

What we claim is—

1. A top bolster for car-trucks, combining in its structure two parallel beams spaced by interposed end blocks, top and bottom center 10 plates connected by bolts passing between the two beams and centrally perforated for the passage of the king-bolt between the spaced beams, and longitudinal truss-rods, one for each beam, connected at their ends with cross- 15 bars, which abut against the beams, substantially as described.
2. In a top bolster for car-trucks, the combination, with the parallel spaced beams having intervening blocks at their ends and braced 20 by longitudinal truss-rods, of top and bottom

center plates having projecting central flanges arranged in the spaces between the beams and perforated for the passage of the king-bolt, substantially as set forth.

3. In a top bolster for car-trucks, the combination of the side beams, *a a*, having intervening blocks *b* at their ends, perforated top and bottom center plates, *G H*, having central flanges, *c*, and nipples *d*, and the longitudinal truss-rods *g g*, substantially as and for 25 30 the purpose shown and described.

In testimony whereof we have hereunto set our hands in the presence of two subscribing witnesses.

WILLIAM J. MCCOY.
BART DEAN.
